SUCTION CLEANER

Llewellyn A. Griffith, Buffalo, N. Y.

Application December 21, 1944, Serial No. 569,173

7 Claims. (Cl. 15—14)

This invention relates to suction cleaners and particularly to improvements in suction cleaners of the kind generally known in the art as tank type cleaners.

In general, tank type cleaners usually comprise a cylindrical casing adapted to rest lengthwise on a floor or the like and the operating motor thereof is adapted to draw air in at one end of the cylinder and discharge it at the other. Such cleaners are generally arranged so that a flexible hose may be selectively connected to either end of the cylinder whereby the appliance may be employed in conventional suction cleaning or, by connection to the opposite end, as a blower or air pressure discharge device for various purposes.

In the prior art various devices have been proposed for detachably connecting the flexible hose or conduit to one or the other end of the cleaner tank. Such devices have been in the nature of conventional bayonet joints, detent button interlocks, and others. They have in general been cumbersome and awkward to manipulate, especially in the hands of housewives who are frequently not familiar with the operation of mechanical devices. The use of auxiliary attachments or modes of operation is frequently governed by and dependent upon the facility with which the alternative mode of operation may be rendered available, and thus rendering an auxiliary mode of operation more quickly and conveniently available has the practical result of actually widening the potentialities of the appliance as a whole.

According to the present invention the flexible conduit or hose of a tank type suction cleaner is associated with the cleaner for association with the cleaner proper in a semipermanent manner, but in such a way that it may readily and quickly be swung between opposite positions where it has sealed fluid connection with the apertures provided at the opposite ends of a suction cleaner of the kind here under consideration. The proposed arrangement is such that a reversal from one end of the cleaner to the other of the hose connection may be accomplished by merely manipulating the outer or nozzle end of the hose without even necessitating stooping over on the part of the user.

While a specific embodiment of the principles of the present invention is set forth in detail in the accompanying drawing and is described in the following specification it is to be understood that neither the spirit nor scope of the invention

are limited thereto or otherwise than as defined in the appended claims.

In the drawing:

Fig. 1 is a top plan view of one form of the device of the present invention;

Fig. 2 is a side elevational view thereof;

Fig. 3 is an end elevational view thereof; and
Fig. 4 is a fragmentary elevational view, partly in cross section, showing in detail the manner in which the conduit engages one of the ends of the cleaner casing.

Throughout the several figures of the drawing, like characters of reference denote like parts and the numeral 10 designates a cylindrical casing of a tank type suction cleaner whose interior arrangement, as to fan, operating motor, dirt bag and the like, are entirely conventional and accordingly are not illustrated. As viewed in Figs. 1 and 2, the right hand end of the cleaner may be the suction end, by reason of which a removable closure cap 11 is provided to permit ready removal of the conventional dirt bag for cleaning and replacement. Conventional clasps 12 retain the end cap 11 in assembled position in a readily detachable manner.

A pair of otherwise conventional supporting runners 13, secured to the casing 10 for supporting the same, extend rearwardly as at 14 a sufficient distance to form, with a rubber collar 15, a tripod for supporting the cleaner in a vertical position while the dirt bag is being removed and replaced. The resilient collar 15 at the outlet end of the tank 10 has a similar counterpart designated 16 at the suction end of the cleaner. As shown in Fig. 4, the collar 16 is disposed about an annular flange 17 which may be formed as a part of and centrally of the end cap 11. The resilient collar 15 at the discharge end, has a similar supporting flange, not shown. It will be noted that the collar 16 extends somewhat beyond the supporting flange 17 to permit its compression in the act of associating the hose therewith.

It may be desired to entirely remove the hose from the cleaner for various reasons, such as in storing or transporting the appliance. For this reason a conventional means for disconnecting the hose may be provided in addition to the arrangement of the present invention. The conventional connecting means comprises a collar rigidly associated with the end of a flexible conduit designated 18. This collar does not appear in Figs. 1, 2 and 4 since it is received entirely within a connecting collar 19 and, as is conventional, is held in place therein by detents 20 which are urged outwardly by spring means not

shown. Disassembly of the conduit or hose 18 from collar 19 is effected by manually pressing the detents 20 radially inwardly and simultaneously withdrawing the conduit 18 from collar 19. It is to be understood that this conventional connecting means need not be employed in the normal use of the cleaner proposed herein.

The collar 19 has fixed thereto, as by welding or in any other convenient way, a pair of supporting arms 22 and 23 which are pivotally attached to the tank 10 centrally thereof by pivot pins 24 and 25 respectively. In the illustrated instance the arms 22 and 23 are offset as shown in Fig. 2 to clear the clasps 12 and, for convenience, the clasps 12 are employed as locating stops and prevent further downward movement of the arms 22 and 23 from the position illustrated in Fig. 2.

The collar 19 has a flange 28 which seats against the resilient collar 16 in Figs. 1, 2 and 4, and is adapted to alternatively seat against the collar 15 at the other end of the cleaner in a substantially identical manner. The collar 28 has upper and lower cam flange extensions 29 and 30, respectively, to facilitate bringing the flange 28 into seating engagement with either of the collars 15 or 16, respectively.

With the parts in the position shown in Figs. 1 and 2 it is merely necessary for the operator to pull upwardly on the outer or nozzle end of the hose which is normally held by the operator, and if necessary the tank 10 may be held down with the operator's foot to insure movement of the collar 19 and its associated flange 28 upwardly away from collar 16. By simple manipulation of the hand held end of the hose the collar 19 may be swung through the arc defined by supporting arms 22 and 23 and the cam face 29 will guide the collar 28 over the outer end of collar 15, partially compressing the latter to insure air tight engagement. Final movement of the collar 19 and flange 28 to a position of concentricity with collar 15 may be effected by the operator's foot.

The limit position of arms 22 and 23 at the left or pressure end of the cleaner is defined by abutments 31 and 32 disposed at opposite sides of the tank 10, and in this way accurate concentricity of the collar 19 and hose 18 with the collar 15 is assured. The cleaner is then arranged to discharge air under pressure through the nozzle end of hose 18. When it is again desired to suck air into the nozzle end of hose 18 the connecting collar 19 and flange 28 may be returned to the position illustrated in Figs. 1 and 2 by a mere reverse operation to that just described. A suitable handle 34 is attached to the tank 10 to facilitate ready portability of the device.

In Fig. 2 a conventional air displacement fan and driving motor therefor are shown in dotted lines at 39 and 40, respectively.

I claim:

1. A suction cleaner comprising a floor-type tank having an air displacing fan and an operating motor therefor disposed therein, an air inlet opening and an air discharge opening at opposite ends of said tank, an extension conduit and means at one end thereof adapted to seat over either of said openings, and supporting arm means fixed to said conduit and extending therefrom to pivotal engagement with said tank substantially medially of said openings, whereby pivotal movement of said arm means through substantially a semi-circle reverses the fluid connection of said conduit with said tank.

2. A suction cleaner comprising a floor-type

tank having an air displacing fan and an operating motor therefor disposed therein, an air inlet opening and an air discharge opening at opposite ends of said tank, an extension conduit and means at one end thereof adapted to seat over either of said openings, supporting arm means fixed to said conduit and extending therefrom to pivotal engagement with said tank substantially medially of said openings, whereby pivotal movement of said arm means through substantially a semi-circle reverses the fluid connection of said conduit with said tank, and stop means associated with said tank and disposed to limit pivotal movement of said arm means and said conduit seating portion at opposite ends of said semi-circular path.

3. A suction cleaner comprising a floor-type tank having an air displacing fan and an operating motor therefor disposed therein, an air inlet opening and an air discharge opening at opposite ends of said tank, a flexible extension conduit and means at one end thereof adapted to seat over either of said openings, and supporting arm means fixed to said conduit and extending therefrom to pivotal engagement with said tank substantially medially of said openings, whereby pivotal movement of said arm means through substantially a semi-circle by manipulation of said flexible conduit reverses the fluid connection of said conduit with said tank.

4. A suction cleaner comprising a floor-type tank having an air displacing fan and an operating motor therefor disposed therein, an air inlet opening and an air discharge opening at opposite ends of said tank, means extending about each opening to provide a seat, an extension conduit and means at one end thereof comprising a seat means engageable with the seat means of either of said openings, and supporting arm means fixed to said conduit and extending therefrom to pivotal engagement with said tank substantially medially of said openings, whereby pivotal movement of said arm means through substantially a semi-circle reverses the fluid connection of said conduit with said tank, at least one of said seat means being axially compressible to insure fluid tight engagement.

5. A suction cleaner comprising a floor-type tank having an air displacing fan and an operating motor therefor disposed therein, an air inlet opening and an air discharge opening at opposite ends of said tank, means extending about each opening to provide a seat, an extension conduit and means at one end thereof comprising seat means engageable with the seat means of either of said openings, and supporting arm means fixed to said conduit and extending therefrom to pivotal engagement with said tank substantially medially of said openings, whereby pivotal movement of said arm means through substantially a semi-circle reverses the fluid connection of said conduit with said tank, at least one of said seat means being axially compressible to insure fluid tight engagement, and a cam face associated with the other of said seat means to facilitate lateral fluid connection.

6. A suction cleaner comprising a floor-type tank having an air displacing fan and an operating motor therefor disposed therein, an air inlet opening and an air discharge opening at opposite ends of said tank, axially compressible seat means extending about each opening, an extension conduit and means at one end thereof adapted to seat against either of said seat means, and supporting arm means fixed to said conduit and ex-

tending therefrom to pivotal engagement with said tank substantially medially of said openings, whereby pivotal movement of said arm means through substantially a semi-circle reverses the fluid connection of said conduit with said tank.

7. A suction cleaner comprising a floor-type tank having an air displacing fan and an operating motor therefor disposed therein, an air inlet opening and an air discharge opening at opposite ends of said tank, axially compressible seat means extending about each opening, an extension conduit and means at one end thereof adapted to seat against either of said seat means, and sup-

porting arm means fixed to said conduit and extending therefrom to pivotal engagement with said tank substantially medially of said openings, whereby pivotal movement of said arm means through substantially a semi-circle reverses the fluid connection of said conduit with said tank, and cam means at said end of said conduit to cam over and compress said seat means during final movement of said arm means to insure fluid tight engagement of said conduit with either of said openings.

LLEWELLYN A. GRIFFITH.
